Primary Examiner — Brian N Vinson*(74) Attorney, Agent, or Firm* — Simpson & Simpson, PLLC(57) **CLAIM**

The ornamental design for a dress-shaped organizer, as shown and described.

DESCRIPTION

FIG. 1 is a front perspective view of the dress-shaped organizer of the present invention;

FIG. 2 is a front elevational view of the invention shown in FIG. 1;

FIG. 3 is a rear elevational view of the invention shown in FIG. 1;

FIG. 4 is a right side elevational view of the invention shown in FIG. 1;

FIG. 5 is a left side elevational view of the invention shown in FIG. 1;

FIG. 6 is a top plan view of the invention shown in FIG. 1; and,

FIG. 7 is a bottom plan view of the invention shown in FIG. 1. The dotted line disclosure in the views is understood to represent conventional stitching.
